UNITED STATES PATENT OFFICE.

ALEXANDER H. RUDD AND WALTER P. MENDENHALL, OF MEDIA, PENNSYLVANIA.

PLAYING-CARD.

SPECIFICATION forming part of Letters Patent No. 449,274, dated March 31, 1891.

Application filed November 7, 1890. Serial No. 370,620. (No model.)

To all whom it may concern:

Be it known that we, ALEXANDER H. RUDD and WALTER P. MENDENHALL, both of Media, county of Delaware, State of Pennsylvania, have invented a certain new Game, of which the following is a true and exact description, reference being had to the accompanying drawings, which form a part of this specification.

Our invention relates to a game of cards which we have devised, and which consists of a pack of playing-cards especially designed and adapted for the said game. The pack consists of six suits of five cards each, the cards of each set being marked, respectively, "15," "30," "40," "Advantage," and "Game;" and in addition to the regular suits an additional odd suit of one or preferably two cards, which we call "bisque cards," are provided to make up the complete pack.

In the drawings, the seven figures represent a suit of five cards, which are indicated in Figures 1 to 5, inclusive, and two bisque cards, indicated by Figs. 6 and 7.

The game is played in the following way: The pack, preferably consisting of thirty-two cards, as described, is shuffled, and five cards dealt to each player, the remainder of the pack being placed face upward on the table.

One of the players then leads, and the trick is taken by the player playing the highest card of the suit, or one of the bisque cards, which takes the place of trumps. The winner of the trick then places it face downward on the table, each player draws a card from the pack, and another trick is then played, and so on until the pack and hands are exhausted, or until game is declared. The winning of the game is determined by the player who first takes all five cards of one suit and declares the same or announces the fact. If no player thus declares game during the playing of the cards, the winner is determined after all the cards are played by ascertaining which of the players has a full suit in the tricks taken by him, and if more than one has such a suit the bisque cards may then be counted to determine which of two or more players is the winner of the game.

The above outline of the game is sufficient to explain its general character. It may of course be modified and additional rules and provisions made.

Having now described our invention, what we claim as new, and desire to secure by Letters Patent, is—

A pack of cards consisting of six suits, each of five cards, marked, respectively, "15," "30," "40," "Advantage," and "Game," and an additional card or cards.
